UNITED STATES PATENT OFFICE

2,559,201

MOTOR ACTUATED DISPLAY FIGURE

Abraham Abbot Schy and Stuart Theodore Schy,
Los Angeles, Calif.

Application October 10, 1949, Serial No. 120,462

1 Claim. (Cl. 46—120)

1

Our invention relates to a figure or figurine, preferably shaped to represent a human being and mounted so as to move and at the same time, impart movement to an associated accessory or member, thus providing an attractive and interesting display piece or advertising novelty, adaptable for use in the show windows and show cases of merchandising establishments, or by giving the figure the shape of an animal such as a bear, elephant, seal or monkey, the device provides an interesting and attractive mechanical toy.

A further object of our invention is, to provide simple and effective means actuated by a motor, preferably electric, for imparting simultaneous movement to the figure and to a movable part or part associated therewith.

With the foregoing and other objects in view, our invention consists in certain novel features of construction and arrangement of parts, hereinafter more fully described and claimed, and illustrated in the accompanying drawing, in which:

Fig. 1 is a front elevational view of a moving display figure constructed in accordance with our invention,

Fig. 2 is an enlarged vertical section taken transversely through the lower portion of the body of the figure and the movement imparting means,

Fig. 3 is a horizontal section taken on the line 3—3 of Fig. 2,

Fig. 4 is a vertical section taken on the line 4—4 of Fig. 2,

Fig. 5 is a view looking upward and indicated by the arrow 5 in Fig. 4.

Referring by numerals to the accompanying drawing which illustrates a preferred embodiment of our invention, 10 designates a base, preferably formed of sheet metal, plastics or the like, within which is a small motor 11, preferably electric, supported by brackets 12 and mounted on the lower end of the motor shaft 13 is a short crank arm 14.

Rigidly secured to the top of base 10 and to the plate 15 which supports motor 11, is a sleeve 16, on the lower end of which is secured a crank arm 17, slightly longer than crank arm 14.

A pitman 18 connects the crank arms 14 and 17; arranged for rotation in sleeve 16 is a tubular shaft 19 which extends upwardly from the top of base 10, and is rigidly secured in the lower portion 20 of a figurine, which may simulate a dancing girl, bathing girl, mannequin or the like. Where this lower portion 20 of the figure is

5 molded or cast from metal, plastics or the like, shaft 19 is embedded fixedly therein. Lower portion 20 includes the limb and hip portions of the finished figure and detachably connected to the top of said lower portion, is the lower end of the upper portion 21 of the figure, which includes the body, arms and head representing parts.

10 A chamber or recess 22 is formed in the upper portion of lower body member 19 and a corresponding chamber 23 is formed in the lower portion of upper body member 21.

Depending from opposite sides of the lower edge of the wall of upper body member 21, are 15 lugs 24, which bear against the inner face of the upper edge of the wall of lower member 20 and screws 25 pass through the wall of the lower member into said lugs, thereby detachably connecting the upper and lower body parts.

20 A fixed rod or shaft 26 extends through tubular shaft 19 and is secured at its lower end to a bracket 27 depending from plate 15 and the upper end of this rod above the upper end of tubular shaft 19, carries a fixed bevel pinion 28. A 25 horizontally disposed shaft 29 is journaled in bearings 30, formed in the meeting edges of the walls of upper and lower body members 21 and 20 and carried by said shaft is a bevelled pinion 31 which meshes with pinion 28.

30 Secured on the end of shaft 29 in front of the body is an accessory or decorative member 30a, for instance, simulated fan, bouquet, flag or the like and one of the hand representing members 35 of the figure may terminate adjacent the lower end of said member as seen in section, in Fig. 3, thus giving the appearance of said hand grasping said member.

In operation, tubular shaft 19 is partially rotated, first in one direction and then in the other, by driving connections 14, 18 and 17 from the motor shaft 13 and thus the figure carried by the upper portion of said shaft 19, will turn part way around intermittently in opposite directions.

45 Simultaneously, the engagement of pinion 31 with pinion 28 will partially rotate shaft 29, first in one direction and then in the other, so as to swing the fan, bouquet, flag or other article across the face and upper portion of the body of the figure which movement combined with the turning movements of the body produces the desired attractive and animated effects.

Thus, it will be seen that we have provided a motor actuated display figure or figurine which 55 is simple in structure, inexpensive of manufac-

ture and very effective in performing its intended functions.

Minor changes in the size, form and construction of the various parts of our improved display figure or toy may be made and substituted for those herein shown and described without departing from the spirit of the invention, the scope of which is set forth in the appended claim.

We claim as our invention:

In a motor actuated display figure or toy, a 10 housing, a vertically disposed tubular shaft mounted for rotation in said housing and projecting upwardly therefrom, motor driven means within the housing for driving said tubular shaft first in one direction and then in the other, a fixed shaft extending through said tubular shaft, a body representing member secured to said tubular shaft above said housing, said body representing member being formed in two detachably connected parts, a horizontal shaft journalled between said parts, a pinion secured intermediate

5 the ends of said horizontal shaft, a pinion secured to the upper end of said fixed vertical shaft and meshing with the pinion on said horizontal shaft and a simulated accessory mounted on the forward end of said horizontal shaft in front of said body representing member.
